UNITED STATES PATENT OFFICE.

FRIEDRICH BEYER, OF SIEGMAR, GERMANY.

DEVICE FOR CUTTING AND SETTING BRICKS, &c.

No. 821,453.

Specification of Letters Patent.

Patented May 22, 1906.

Application filed February 29, 1904. Serial No. 195,832.

To all whom it may concern:

Be it known that I, FRIEDRICH BEYER, manufacturer, a subject of the German Emperor, and a resident of Siegmars, near Chemnitz, in the Kingdom of Saxony, German Empire, have invented certain new and useful Improvements in Devices for Cutting and Setting Bricks Made by Bar-Presses, of which the following is a specification.

10 My invention relates to a new device for cutting and setting bricks manufactured by means of the so-called "stream-brick cutter."

15 The advantage of my device lies in the fact that by means of the same more than three bricks may be removed at a time, as the bricks cut off on the bar or stream of clay may be automatically separated into groups of two or three, with sufficient space between them to allow of putting the hand between.

20 This is attained by the special construction of the cutting device which is illustrated on the accompanying drawings—viz., in—

Figure 1 in a side view with cut bricks; Fig. 2 in a front view, whereas Fig. 3 is a ground 25 plan. Fig. 4 shows how by a shifting of the usual sliding carriage the groups of bricks are separated, whereas Fig. 5 shows a section according to line A B of Fig. 4, and Fig. 6 illustrates the mode of automatically disengaging the mechanism turning the rollers.

Similar letters refer to similar parts throughout the several views.

The new apparatus arranged on a cutting device of the usual construction has the 35 special feature that there are arranged friction-wheels *e* and *f* on the rollers *a* and *b* near the end of the bar or stream of clay *d*, which coöperate with a friction-bar *i*, arranged on the frame. By shifting the carriage *k*, supporting the rollers *a* and *b*, these rollers are rotated as their wheels *e* and *f* roll upon the bar *i*, and thereby somewhat roll away the two or three cut bricks lying on them. In order to give to the first brick a rolling support, the stop-square *m* is so arranged that it may be tilted and is provided with rollers *n*.

The working of the device is therefore the following: According to whether four or six bricks are to be cut at a time, four or more 50 wires *o* (the former is here supposed) are stretched out in the bow *p* of the cutter. When the bar of clay, which is moved forward in the usual manner, arrives at the square *m*, the workman presses down the bow and four bricks are cut off. Now the carriage *k* is shifted in the usual manner in

the direction of the arrow in Fig. 4. By this shifting is produced the gap *x*, the same as with the usual process. By the shifting of the carriage *k* and the rollers *a* and *b* the 60 wheels *e* and *f* roll upon the bar *i* and through the rotation of the rollers resulting therefrom the first two bricks are moved forward a little, pushing thereby the stop-square *m* into its horizontal position, and the first brick is 65 placed upon the said stop-square *m*, as shown in Fig. 4. A second gap *y* is thereby produced, and the cut bricks are thus divided into two sections and can be taken off simultaneously by two removers. In this way it is 70 possible to remove with this cutting device double the number of bricks attained by other systems. As the advancing bar or stream of clay on its touching the rollers *a* and *b* meets with resistance, as these rollers 75 are checked in their rotation by their friction-wheels resting against the bar *i*, the driving mechanism ought to be disengaged by hand during this period. In order to avoid this, in the device illustrated on the accompanying 80 drawings the mechanism turning the rollers is automatically disengaged while the stream of clay passes over the rollers *a* and *b*; but as also during the return of the carriage the rollers are not required to rotate they remain also disengaged during this period. 85 The engaging and disengaging is effected automatically by the arrangement that the bar *i* is pressed against the rollers *e* or is separated from the same by its own weight.

The rack *i* is driven by a projection *s*, arranged at a suitable place of the frame, and a roller *t*, oscillatingly suspended by means of an arm from the rack *i* in a suitable bending of same. This bending is formed in such a 95 manner that the roller *t* pushes against its inner edge when the carriage is moved in the direction of the arrow in Fig. 4, thereby holding the roller-arm in vertical direction, so that the roller *t* projects below the lower edge of 100 the rack *i*; but when the carriage is moved in the direction of the arrow in Fig. 6 no projection of said roller *t* occurs, as the bending of the rack *i* is wide enough to allow then a free yielding of the arm with the roller *t* in the direction of the carriage movement.

As long as the stream of clay is being advanced, and thus passes over the rollers *a* and *b*, the rollers are not in contact with the bar *i*, as the latter, held by the roller *t*, which rests on the frame, is in the lowered position. (Shown in Fig. 1.) The mass of clay can therefore in 110

its advance turn the rollers *a* and *b*, there being no obstacle in the way; but if after the cutting—that is to say, after the separation—of a corresponding number of bricks 5 from the mass of clay the carriage is moved in the direction of the arrow, Fig. 4, for the purpose of forming the interspaces the projection *s* on the frame passes under the roller *t*, and the bar *i* during this time presses firmly 10 against the friction-wheels *e f*. The rollers *a* *b* are rotated and remove the bricks lying on them away from the bricks lying on the non-rotating rollers. When this movement is completed, the rack descends again, being no 15 longer held by the projection *s*. If now the carriage is moved back in the direction of the arrow, Fig. 6, the roller *t* rises up to the projection *s*; but it cannot raise the bar *i*, as it does no longer project below the lower edge 20 of the bar *i*, as stated above. The carriage therefore goes back without the rollers *a* *b* being influenced by the bar *i*.

Having now particularly described and ascertained the nature of my said invention and 25 in what manner the same is to be performed, I declare that what I claim is—

1. A device for cutting and setting bricks made by a bar-press, comprising in combination rollers at the end of the bar of clay being 30 provided with means adapted to move the bricks forward in groups with gaps between the end of the clay-bar and after every group

of two or more bricks said means consisting of wheels *e*, *f* connected to the rollers *a*, *b* and adapted to coöperate with a bar *i* fitted 35 on the frame of the press, substantially as described and shown and for the purpose set forth.

2. A device for cutting and setting bricks made by a bar-press, comprising in combination 40 rollers at the end of the bar of clay being provided with means adapted to move the bricks forward in groups with gaps between the end of the clay-bar and after every group of two or more bricks, said means consisting 45 of wheels *e*, *f* connected to the rollers *a*, *b* and adapted to coöperate with a bar *i* fitted on the frame of the press, said bar *i* being provided with means which press it against the driving-wheels *e* and *f* by a projection *s* on the frame, 50 when the carriage separates the bricks from the mass of clay, while said means remove the bar *i* from the driving-wheels as long as the carriage moves backward and the mass of clay is being advanced, substantially as described and shown and for the purpose set forth.

In witness whereof I have hereunto signed my name, this 25th day of January, 1904, in the presence of two subscribing witnesses.

FRIEDRICH BEYER.
